COVER AND CAN HANDLING DEVICE

Willard S. Campbell, Hampshire, Ill., assignor,
by mesne assignments, to Cherry-Burrell Corporation,
Chicago, Ill., a corporation of Delaware

Application November 13, 1940, Serial No. 365,435

3 Claims. (Cl. 198—75)

My invention relates to a construction for properly timing the receiving, passing through and discharging of a can and its cover.

Among the objects of my invention is to provide a construction which receives a can and its cover, passes them through the machine one above the other, and discharges them together. This prevents confusing covers with cans with which they do not belong and insures that the can will receive its cover and no other cover. This is extremely important where cans and covers of many different concerns are involved.

My construction provides a single cover for each can and a single can for each cover, and prevents a situation where there would be several cans for each cover, or several covers for each can.

In my construction the cover proceeds from the entrance through the greater portion of the machine in vertical position and then assumes a horizontal position adjacent the exit so as to be dropped onto the can. Means is provided so that the covers are firmly positioned on the cans when they are discharged, thereby preventing exposure of the interiors of the covers and cans to bacteria and contamination from the atmosphere.

My construction is simple and eliminates complicated machinery. It operates more silently, avoiding all unnecessary noise. Those portions of the construction that receive and discharge the covers are can operated—that is to say, the cover movements are initiated and controlled by the movements of the cans in the can handling portion of the construction.

My construction involves such other objects, advantages and capabilities as will later more fully appear and which are inherently possessed by my invention.

While I have shown in the accompanying drawings a preferred form of my invention, yet I desire it understood that the same is susceptible of modification and change without departing from the spirit of my invention.

Referring to the drawings, Fig. 1 is a diagrammatic side elevational view broken in two portions to emphasize the entrance and exit portions of the device; Fig. 2 is an end elevational view on line 2—2 of Fig. 1, showing in detail the exit portion of the device; Fig. 3 is an enlarged detail plan view showing the construction for the turning of the cover from vertical to horizontal position; Fig. 4 is an enlarged top plan view of the mechanism on the lower level; Fig. 5 is a side elevational view of the mechanism shown in Fig.

4; Fig. 6 is a side elevational view showing the upper and lower levels with the connection therebetween at the entrance portion of the device; Fig. 7 is an enlarged detail view of the stop lever mechanism on the upper level; Fig. 8 is a detail perspective view of the rack.

The embodiment selected to illustrate my invention is ordinarily associated with a straight-away washer, sterilizer and drier, but I am primarily concerned with the entrance, passage and discharge of cans and covers and not with their treatment during the passage.

Said embodiment comprises a frame 10 with spaced side walls 11 forming an interior 12 with an open entrance 13 and an open exit 14 to respectively receive and discharge the cans and covers. A support or track 15 attached to the frame 10 is provided in the lower portion or level and extends substantially the length of the interior 12. Another support or track 16 attached to the frame 10 is provided in the upper portion or level above the support 15 and extends substantially the length of the interior. The cans are received, carried through and discharged on the lower level and the covers on the upper level.

Adjacent the entrance 13 at the lower level, bearings 17 are attached to side walls 11. A rotatable shaft 18 extends between bearings 17. Spaced sprockets 19 are mounted on shaft 18. Spaced main chains 20 engage sprockets 19 and turn shaft 18. The main chains 20 extend through the interior 12 of the machine on the lower level track 15 to sprockets 21 attached to shaft 22 rotatable in bearings 23 in bracket 24 which is attached to frame 10. Attached to and driving the shaft 22 is a pulley 25 driven in turn by a belt 26 connected to and driven by a source of power.

Also mounted on shaft 18 and to one side of sprockets 19 is drive sprocket 27. Positioned ahead of bearings 17 and in the side walls 11 is another pair of spaced bearings 28 to rotatably receive another shaft 29. Chain 30 extends between drive sprocket 27 and driven sprocket 31 mounted on shaft 29. Drive sprocket 27 has twice as many teeth as driven sprocket 31. Driven shaft 29 rotates twice as fast as drive shaft 18.

Mounted on shaft 29 is sprocket 32 centrally positioned laterally with respect to spaced sprockets 19. Sprocket 32 drives chain 33 which extends toward entrance 13 to engage idler sprocket 34 which is rotatably mounted on a stud 35 which is attached to bracket 36 which is a part of platform 37. The platform 37 is hingedly attached to track 15. Mounted on chain 33 is a plurality of spaced counter-balanced lugs 38.

Mounted on main chains 20 is a plurality of spaced dogs 39.

Attached to the frame 10 and extending inwardly between shafts 18 and 29 is a support 40. A rod 41 is rotatably attached to support 40. Attached to the inner end of rod 41 and adjacent the outer main chains 20 is a trip lever 42 normally in upright position. Attached to the outer end of rod 41 is another lever or arm 43. A connecting member 44 is attached on one end to arm 43. The connecting member 44 extends upwardly and its other end is attached to one end of a short chain 45. The other end of the short chain 45 is attached to spring 46 which in turn is attached to a hook 47 which is attached to the frame 10. The tension of spring 46 holds short chain 45 in engagement with sprocket 48. This sprocket 48 is attached to shaft 49 which is rotatably attached to bracket 50 attached to frame 10. A lever 51 normally in upright position is attached to the shaft 49 adjacent its inner end. Another lever 52 is centrally pivoted to guide 53 which extends diagonally downwardly through entrance 13 into the upper level of the interior 12. Said lever 52 has a slot 54 in its forward portion to slidably receive pin 55 attached to lever 51. When lever 51 is moved downwardly to a horizontal position pin 55 slides to the rear of slot 54 and pivots lever 52 from a horizontal to a vertical plane so that the rear portion 56 of lever 52 forms a stop.

The inner end of guide 53 within the upper level of interior 12 is pivotally and adjustably attached to upper track 16. An upper chain 57 travels on upper track 16 between drive sprocket 58 and idler sprocket 59. Idler sprocket 59 is attached to shaft 60 rotatable in bearings 61 attached to frame 10.

Drive sprocket 58 is attached to shaft 62 rotatable on bearings 61 attached to frame 10 and driven by gear wheel 63 through a chain 64 connected to a suitable source of power.

Also mounted on drive shaft 62 is a drive sprocket 65. A chain 66 extends between drive sprocket 65 and driven sprocket 67 attached to driven shaft 68 rotatably attached to bearings 69 on frame 10. Spaced sprockets 70 are also mounted on driven shaft 68. Spaced light chains 71 extend forwardly between sprockets 70 and idler sprockets 72 mounted on shaft 73 rotatably attached to bearings 74 supported by bracket 75 attached to frame 10. Drive sprocket 65 has twice as many teeth as driven sprocket 67 and light chains 71 travel twice as fast as chain 66. A track 76 attached to frame 10 is provided for light chains 71. Track 76 extends on a downward curve through the exit 14 toward a rack 77, the inner end of which is pivotally and adjustably attached to shaft 73 which rotates on bearings 74 attached to frame 10.

A shaft 80 is rotatably attached to bearings 81 in the frame 10 adjacent the top of the upper level of the interior 12. Mounted on said shaft 80 is an eccentric cam 82. A lever 83 is mounted on shaft 84 which is rotatably attached to bearings 85 in frame 10. Fastened to shaft 84 is a positioner 86. The positioner 86 has a diagonally downwardly extending portion 87 and an integral vertical portion 88 to which is adjustably attached a horizontal member 89.

Rotatably attached to frame 10 is a vertical rod 90 having a horizontal bottom portion 91. Adjacent the top of rod 90 is a stop 92 positioned to engage stop 93 on shaft 84. A spring 102 ex-

tends between frame 10 and horizontal portion 91 of rod 90.

Shaft 80 has a sprocket 94 operated by chain 95 connected to a suitable source of power.

5 A plurality of guide rails 96, 97 and 98 extends from the entrance 13 at the upper level along upper track 16. Guide rails 96 and 97 are positioned along the inner side of the track 16. Guide rail 98 is positioned along the opposite or outer side of the track at medium height, with guide rail 97 positioned higher than guide rail 96 and guide rail 98 positioned lower than guide rail 97. At approximately the farthest point where the track 16 and light chains 71 extend within the interior 12, guide rail 97 ends in a downward and inward curve 99. Guide rail 96 ends short of 97, and 98 continues to any further desired point within interior 12 and is shown as ending short of exit 14. The guide rails are attached to frame 10 by any suitable means.

In use an operator places a can through the lower level of entrance 13 in inverted position on platform 37. A counterbalanced lug 38 on chain 33 contacts the can on the inside neck portion and moves it at double speed to main chains 20.

At about the same time as the operator places the can on platform 37 he places the cover in vertical position through the upper level of entrance 13 on guide 53 and the cover rolls on its edge rapidly down the inclined guide until it contacts lever 51 which is normally in upright position. The cover remains in this position until it is released for further movement by operation of the can, as will now be fully set forth.

30 35 While the movement of the cover is stopped by lever 51 the outer back of the neck of the can is contacted by one of the dogs 39 on main chains 20 and moved thereon. As the can moves within the interior 12 it contacts trip lever 42 which is normally in upright position and moves it to a horizontal position. This rotates rod 41 and pulls arm 43 downwardly, also pulling connecting member 44 and moving short chain 45. This movement of short chain 45 moves sprocket 48, 40 45 rotatable shaft 49 and finally lever 51. The movement of lever 51 is to a horizontal plane, removing it as a stop against the cover and permitting the cover to move onto upper chain 57. When lever 51 moves to a horizontal position, 50 55 second lever 52 is pivoted so that its rear portion 56 assumes a vertical position, acting as a stop to prevent any more covers from passing. Otherwise more than one cover might go through to upper chain 57 while lever 51 is in horizontal non-stopping position.

When the can passes by the lever 42 and no longer contacts the same, spring 46 moves trip lever back to normal upright position by pulling the connecting member 44 and arm 43 upwardly.

60 Spring 46 also pulls chain 45 in the other direction, moving sprocket 48 and its rotatable shaft 49. Lever 51 then returns to normal upright position and second lever 52 to normal horizontal position. Any second cover prevented further 65 entrance by rear portion 56 of second lever 52 is stopped from further progress by the now upright lever 51.

The cans and covers continue their progress within the interior 12, with the cans travelling on the chains 20 of the lower level track 15 and the covers moving above their respective cans on chain 57 of the upper level track 16. There are spaced dogs 103 on chain 57.

70 75 At the end of main chains 20 a turning device 100 is provided so that the cans may be turned

from inverted to upright position. This turning device is set forth in detail in my co-pending application for patent on Turning device for milk cans and other articles, Serial No. 353,239, filed in the United States Patent Office on August 19, 1940. At the end of the turning operation each can is deposited on a platform 101 which is located below rack 77 and positioner 86.

In order that the cover will be in position in time to be placed onto its respective can, the cover when it reaches the end of guide rail 96 is directed by curve 99 to fall by gravity in a horizontal position onto light chains 71. The light chains travelling with double speed move the cover so that it falls into rack 77 in plenty of time for its can which is about to be deposited on platform 101 below in upright position from turning device 100. Positioner 86 in its lower position over rack 77 prevents the cover from leaving the rack 77 too soon. As the can passes to platform 101 the can swings horizontal bottom portion 91 of vertical rod 90, and stop 92 of said rod is released from engagement with stop 93 of shaft 84, allowing lever 83 to come in contact with cam 82, thereby raising positioner 86 above rack 77 and releasing the cover so that it falls onto the open mouth of the waiting can on platform 101. Further in the cycle of cam 82, lever 83 is again contacted to raise and then lower positioner 86 against the cover, pressing the cover against the can, thereby sealing it and preventing contamination. When the can has passed on or been otherwise removed from platform 101, spring 102 moves rod 90 to normal position with its stop 92 engaging stop 93 of the shaft 84 so that lever 82 is out of position for engagement with cam 82. Positioner 86 is then in its lower position over rack 77.

Having thus described my invention, I claim:

1. In a device of the class described, a frame having an entrance, a lower level track attached to and within said frame and having a conveyer chain mounted thereon, said combined track and chain being adapted to receive and carry cans, an upper level track attached to and within said frame and having a conveyer chain mounted thereon, said combined track and chain being adapted to receive and carry can covers, a lower lever movably attached to said frame adjacent the lower level track, an upper lever movably attached to said frame adjacent said upper level track, said upper lever normally in upright position to prevent the passage of a cover thereby, a connecting member extending between said levers, said lower lever normally in upright position and adapted upon being contacted by a can passing on said lower level track to move to horizontal position and through said connecting member to move said upper lever to horizontal position to permit a cover to pass thereby, and a spring attached to said connecting member and said frame and adapted upon the can passing said lower lever and releasing contact thereon to move said connecting member to return said lower lever to upright position and to also return said upper lever to upright position to prevent another cover from passing thereby.

2. In a device of the class described, a frame having an entrance, a lower level track attached to and within said frame, a power operated lower

level chain operable on said track and adapted to receive and carry cans, an upper level track attached to and within said frame, a power operated upper level chain operable on said track and adapted to receive and carry can covers, a lower lever movably attached to said frame adjacent the lower level chain, an upper lever movably attached to said frame adjacent said upper level chain, said upper lever normally in upright position to prevent the passage of a cover thereby, a connecting member extending between said levers, said lower lever normally in upright position and adapted upon being contacted by a can passing on said lower lever chain to move to horizontal position and through said connecting member to move said upper lever to horizontal position to permit a cover to pass thereby, and a spring attached to said connecting member and said frame and adapted upon the can passing thereby and releasing contact thereon to move said connecting member to return said lower lever to upright position and to also return said upper lever to upright position to prevent another cover from passing thereby.

3. In a device of the class described, a frame having an entrance, a power operated double speed chain movably attached to said frame and extending from the entrance a short distance into the interior of the device at the lower level thereof, a lower level track attached to said frame and leading from the inner end of the double speed chain farther into the interior of the device, a power operated lower level main chain operable upon said lower level track, said double speed chain and said lower level chain adapted to receive and carry cans, a guide leading from the exterior of the device and extending diagonally downwardly through the entrance a short distance into the interior of the device at the upper level thereof, an upper level track attached to said frame and leading from the inner end of said guide farther into the interior of the device, a power operated upper level chain operable upon said upper level track, said guide and said upper level chain adapted to receive and carry covers, a lower lever movably attached to said frame adjacent the beginning of the lower level main chain, an upper lever movably attached to said frame adjacent the beginning of the upper level chain, a third lever pivotally attached to said guide and to said upper lever, a connecting member extending between said lower and upper levers, said lower lever normally in upright position and adapted upon being contacted by a can passing on said lower level main track to move to horizontal position and through said connecting member to move said upper lever to horizontal position to permit a cover to pass thereby, said upper lever moving said third lever to upright position to prevent the passage thereby of any more covers, and a spring attached to said connecting member and said frame and adapted upon the can passing said lower lever and releasing contact thereon to move said connecting member to return said lower lever to upright position, to return said upper lever to upright position and to return said third lever to horizontal position to prevent another cover from passing thereby.

WILLARD S. CAMPBELL,
